CLAIM

The ornamental design for an internal combustion engine for technical models, as shown and described.

DESCRIPTION

FIG. 1 is a perspective view of an internal combustion engine showing my new design;

FIG. 2—is a front elevational view thereof;

FIG. 3—is a rear elevational view thereof;

FIG. 4—is a right side elevational view thereof;

FIG. 5—is a left side elevational view thereof;

FIG. 6—is a top plan view thereof;

FIG. 7—is a bottom plan view thereof.

FIG.1

FIG. 2

FIG. 3

FIG. 6

FIG. 7
